2 Claims. (Cl. 42—1)

This invention relates to a grenade launcher.

Rifle, pistol and other firearm grenades are generally fired with the aid of a grenade launcher secured to the end of the barrel of the firearm.

Hollow charge anti-tank grenades, which are used in modern armies, have a tail which caps the launcher and are fired with a blank cartridge, being propelled solely by the expansion of the gases.

A rifleman inadvertently using a ball cartridge for firing a grenade, with the hitherto available equipment, may cause an accident which might be fatal to him, since the ball would explode the grenade on the launcher. In training, an infantryman is duly warned of the risks run, and instruction manuals are strict in this respect. Nevertheless in operational firing, owing to bad visibility or night conditions, it is always possible to make a mistake with the cartridges, since ball cartridge- and grenade-firing may alternate.

The present invention aims at obviating the foregoing risk and at providing the firer with a grenade launcher equipped with a safety device adapted to prevent the explosion of the projectile even if the operator inadvertently places in his rifle or forgets to remove from it, a ball cartridge at the time of firing the grenade.

The grenade launcher of the present invention, which is intended to serve for firing rifle or other firearm grenades, is of the type comprising a tube serving as barrel and provided at its rear end with a manual fixing means connecting it rigidly to the firearm.

The grenade launcher of the present invention comprises interiorly an axial chamber of a diameter greater than that of the bore of the gun barrel and forming an extension of the latter, a metal core of generally oblong shape and provided at its periphery with longitudinal cavities leaving a normal passage for the gases of a blank cartridge used for firing the grenade. Said metal core thus housed in said chamber is secured to the wall of the latter by retaining means adapted to yield under the shock of an inadvertently fired ball cartridge and to drive said core towards the front where it is stopped at the front part of said chamber leading into the tube of the grenade launcher, while the ball is crushed inside a cavity provided at the rear of the core.

By virtue of this construction an error with cartridges therefore does not cause any accident to the rifleman. Moreover, the infantryman, knowing that he is protected from any explosion of the projectile at the muzzle of the gun, has confidence in his weapon, and his action and performance are improved.

According to one embodiment of the invention, the grenade launcher has two transverse apertures leading into said chamber on to the outside surface of the core, between two successive longitudinal cavities in the latter. The retaining means preferably comprises a plurality of pins which are integral both with the launcher and with the core occupying said chamber.

Thus a ball cartridge fired accidentally displaces the

2

safety core towards the front, after shearing the pins, thus freeing the transverse apertures through which the cartridge gases can escape. Any risk of excess pressure in the barrel is thus avoided, and the grenade which falls in front of the muzzle does not explode and is not damaged, since its internal safety device can be unlocked only under the action of an acceleration of a predetermined value, which in such case is not reached. The aforesaid metal core, which is preferably bi-ogival in shape, is hollowed at its front end so as to permit the ball which strikes it to penetrate into said hollow, where it is crushed after having passed through a hood the shape of which promotes the flow of the gases towards the periphery of the core during normal firing with the blank cartridge intended for firing the grenade.

In order to enable the invention to be more readily understood, reference is made to the accompanying drawings which illustrate diagrammatically and by way of example one embodiment thereof and in which:

Figure 1 is a partial axial section on the line 1—1 of Fig. 4;

Figure 2 is a plan view, partly cut away, of a launcher according to Figure 1;

Figure 3 is a section along the line 3—3 of Figure 2; and

Figure 4 is a section along the line 4—4 of Figure 2.

1 denotes the barrel tube of the grenade launcher mounted at the end 2 of a rifle with the aid of a fixing device 3. An axial chamber 4 screwed on to the tube 1 at 5, serves as a housing for an oblong metallic core 6 having ogival ends. Pins 7 penetrating into the body of the core 6 and passing through the wall of the chamber 4 secure said core to said chamber.

The outside surface of the core 6 comprises longitudinal hollows 8 providing passages (four in the embodiment illustrated) between the core 1 and the wall of the chamber 4, the latter communicating with the outside through apertures 9 and 10. An axial and cylindrical inlet 11 provided in the core 6 opposite the end of the rifle is preferably closed by a hood 12 having a rounded head.

The launcher also has an elastic ring 13 serving to retain the grenade (not shown) when the latter is placed on the barrel tube 1. A sighting frame 14, adapted to pivot at 15, can be folded back. In the operative position (Figure 1) the frame 14 masks the field of view of the foresight 16 of the rifle, so that the user automatically remembers to remove the grenade launcher when firing ordinary ball cartridges.

The operation is as follows:

The rifleman, after having placed a grenade on the barrel 1 of the launcher, sights with the aid of the frame 14 and fires. If he has used a blank cartridge, the propulsion gases on encountering the core 6 will diverge and pass through the longitudinal hollows 8 and then penetrate into the barrel-tube 1, projecting the grenade towards the target. If by error the cartridge is a ball cartridge, the ball will penetrate into the cavity 11 of the core 6, yielding a part of its kinetic energy to the latter. The pins 7 are sheared under the shock and the core 6 moves forward until it encounters the part of smaller diameter of the barrel 1, while the gases escape through the transverse apertures 9 and 10 freed by the forward movement of the core.

What is claimed is:

1. A grenade launcher having a front portion to hold a grenade and a rear portion to be fixedly attached to a gun barrel, said rear portion comprising a chamber of greater diameter than the internal caliber of said launcher, a core of generally oblong shape inside said chamber, frangible means to secure said core axially in said chamber, said core having longitudinal passages at its periphery for

3
normally causing propulsion gases to diverge and pass through said longitudinal passages, and said core being adapted to stop an inadvertently fired bullet in the launcher.

2. A grenade launcher as described in claim 1 in which said core has a normally closed rear cavity for receiving an inadvertently fired bullet.
